(57) **CLAIM**

The ornamental design for an electrical plug-in connector, as shown and described.

DESCRIPTION

FIG. 1 is a front perspective view of an electrical plug-in connector showing my new design.

FIG. 2 is a front-view of the electrical plug-in connector of FIG. 1.

FIG. 3 is a rear-view of the electrical plug-in connector of FIG. 1.

FIG. 4 is a top-view of the electrical plug-in connector of FIG. 1.

FIG. 5 is a bottom-view of the electrical plug-in connector of FIG. 1.

FIG. 6 is a left side-view of the electrical plug-in connector of FIG. 1; and,

FIG. 7 is a right side-view of the electrical plug-in connector of FIG. 1.

In the drawings, the broken lines are for the purpose of illustrating environment only and form no part of the claimed design.
